UNITED STATES PATENT OFFICE.

GEORGE E. WHITNEY, OF BRIDGEPORT, CONNECTICUT, ASSIGNOR TO THE INTERNATIONAL PAVEMENT COMPANY, OF HARTFORD, CONNECTICUT, A CORPORATION OF CONNECTICUT.

PRESS.

Application filed April 14, 1922. Serial No. 552,487.

To all whom it may concern:

Be it known that I, GEORGE E. WHITNEY, a citizen of the United States, and a resident of Bridgeport, in the county of Fairfield and State of Connecticut, have invented an Improvement in Presses, of which the following description, in connection with the accompanying drawings, is a specification, like characters on the drawings representing like parts.

This invention pertains to improvements in presses for making compressed units from plastic masses. It has among its objects, the provision of a compact arrangement of a plurality of instrumentalities for forming the units and one in which the strains incident to the operation of the instrumentalities are reduced to a minimum. The invention, however, will be best understood from the following description when read in light of the accompanying drawing of one specific embodiment of my invention selected for illustrative purposes, while its scope will be more particularly pointed out in the appended claims.

In the drawings:—

Fig. 1 shows a central longitudinal section of a machine constructed according to my invention;

Fig. 2 is a section on the line 2—2 of Fig. 1;

Fig. 3 is a section on the line 3—3 of Fig. 2;

Fig. 4 is a detail of part of the mechanism for operating the plungers; and

Figs. 5, 6 and 7 are sections on the lines 5—5, 6—6 and 7—7 of Fig. 4.

Referring to the drawings, which show the embodiment of my invention selected for illustration, I have indicated a mold press of the type shown in my Patent 1,003,561, granted to me September 19, 1911. The press now to be described in common with that shown in my patent includes a base upon which is positioned a cylinder 1 of circular cross-section and containing a vertically reciprocable piston of similar cross-section. This piston in my present invention is split longitudinally on a diametrical plane into two equal rams 3 of the same effective cross-sectional area. Each ram is used for pressing material in a mold to be described.

Rising from the cylinder 1 are columns 5, which support a bulkhead 7 above the

cylinder. The columns in my present embodiment are four in number and are uniformly distributed around the cylinder.

As disclosed in my patent above referred to, in the bulkhead I support a mold block 9 on which is mounted the sliding head 11. In my present invention the mold block is provided with a plurality of mold chambers 13 of number corresponding to the number of rams 3 and as herein shown two such mold chambers and rams are provided.

Cooperating with the mold chambers 13 are mold plungers 15, each of which carries a plunger cap 17, which fits a mold chamber and reciprocates therein.

The mold plungers are supported on the ejecting heads 19, being separated therefrom by the distance blocks 21 and secured thereto by means of the tie bolts 23. The ejecting heads 19 are movable relatively to the rams, being for this purpose supported for reciprocation on the ejecting head guides 25. The ejecting head guides are carried on the rams 3 and are secured thereto by means of stud bolts 27 (Fig. 1) carried by the rams and passing through the flanges 29 of the ejecting head guides. For convenience in assembly, the ejector heads are split on longitudinal planes to provide two parts which are secured together by means of bolts 31 passing through the ears 33 carried by the ejector heads.

In my present invention I have shown the sliding head 11 provided with a central located diaphragm 35, which divides the through passage of said head into a plurality of passages each leading to a mold chamber 13. Extending through the through passage of the sliding head is a feed neck 37 which leads from a hopper or other suitable source of supply of plastic material to be fed to the chambers.

As will be understood from my patent above referred to, the sliding head is reciprocated to open the mold chambers and permit the plastic material to enter said chambers, the parts under these conditions being in the positions illustrated by Fig. 2. After the mold chambers are charged with material the sliding head is moved to close the molds, whereupon the rams are caused to rise to force the plungers 15 into the mold chambers and compress the material therein. The sliding head is then given a further movement in the same direction so as to un-

cover the mold chambers, whereupon the plungers are further raised in the same direction from the intermediate position just described to a final position which acts to 5 force the contents of the mold chambers out of said chambers. The sliding head and plunger are then again moved into the initial position illustrated by Fig. 2 and the operation repeated.

- 10 For causing actuation of the rams the space beneath the same is filled with a liquid, the pressure of which is caused to be raised and lowered by the reciprocations of the displacement member 39. The liquid tends 15 to escape around the outer surface of the rams, which tends to press the rams toward each other and thereby prevent relative movement between them. To eliminate this effect I so form the adjacent surfaces of 20 the rams as to provide the chamber 41 which extends entirely across the cylinder and into which liquid may find its way and act outwardly to oppose the inwardly acting pressure. The contacting surfaces of the 25 rams above and below the chamber 41 are ground to provide as near as possible a fluid tight joint. It will be understood, however, that I may admit pressure liquid to the chamber 41 by conduit means other than 30 that shown or if desirable may employ other means for neutralizing to the desired extent the pressure of the liquid against the outer surfaces of the rams by admitting liquid between them.
- 35 For moving the plungers to eject the material from the molds I provide the arms or levers 43, one being provided for each ejector head and the two being loosely mounted in side by side relation on a rock 40 shaft 45. This rock shaft is journaled in brackets 46 (Fig. 1) which are supported in any convenient manner to a fixed part of the machine, and is oscillated by means of the lever 47, which is fixed to the rock shaft 45 and carries at its end a cam roller 49 co-operating with the cam 51. The lever 47 is provided with an arm 52, which is located beneath a lug 53 carried by the upper arm 43 as viewed in Fig. 6. The shaft 45 also carries in fixed relation thereto an arm 55 similar to the arm 52 of the lever 47, the arm 55 being positioned beneath the lug 53 of the lower arm 43 as viewed in Fig. 6. It will be noticed by this construction 50 that when the cam 51 is in operation, the lever 47 rocks the shaft 45, which causes the arms 43 to oscillate.
- 55 Each arm 43 carries at its end a pivoted block 57 in contact with the under face 59 of the ejecting heads. It will thus be noted that the blocks 57 and arms 43 constitute an abutment for determining the lowermost position of the mold plungers and therefore determine the amount of material which 60 may pass into the mold chambers.

For determining the lowermost position of the blocks 57 the arms 43 are perforated at 61 and through the perforations are passed rods 63 each of which carries at its lower end a buffer spring 65 supporting a 70 buffer plate 67. The arms 43 in their lowermost position rest on the buffer plates.

For adjusting the abutments afforded by the buffer plates 67, each rod 63 has secured to its upper end an eccentric strap 69 co-operating with an eccentric 71. Rotation of the eccentrics in an obvious manner acts to raise or to lower the buffer plates 67. For supporting the eccentrics 71 and for rotating them, one of said eccentrics, namely 75 the lower eccentric as viewed in Fig. 5 is carried by a sleeve 73, while the upper eccentric is carried on a shaft 75 which passes through said sleeve. The shaft is journaled in a bearing 77 carried by one of the columns 5 while the sleeve is journaled in a similar bearing 77 carried by an opposite column 5. The end of the shaft 75 projects beyond the sleeve and carries an arm 79, while the adjacent end of the sleeve carries a similar arm 81. Each arm 79 and 81 carries at its end and in pivotal relation thereto a nut 83. Through each nut 83 extends the screw threaded end 85 of a rod 87 which is held against longitudinal movement by a thrust collar 89 carried by a fixed part of the machine and which rod may be rotated by means of a hand wheel 91. It will thus be seen that by means of the hand wheels 91, the operator may, 90 whether the press is in operation or not, adjust the lowermost position of either of the plungers and thereby determine the amount of material that passes into the mold chambers.

It will be understood that when the arms or levers 43 raise the mold plungers to eject the compressed material from the molds, the movement of said plungers must be sufficient to raise the material to the upper 10 edges 92 of the mold chambers in order that the sliding head may carry the compressed material away from the mold chambers. To compensate for variations in the thickness of the plunger caps 17 and to adjust them 11 with relation to the upper edge 92, each lever 43 carries a wedge 93 which is dovetailed at 95 into the lower side of the lug 53 of said levers. Each wedge 93 carries an upstanding end portion 95 through which 12 passes a stud bolt 97 secured to the side of the lug 53 as is clearly illustrated by Fig. 4. The lower faces of the wedges rest on semi-cylindrical blocks 99 carried in semi-cylindrical recesses 101 on the arms 55. Extending through each block 99 are a pair of bolts 103, which by means of the springs 105, act to yieldingly hold the blocks in the recesses 101. It will be noted that as I provide a rocking support for the 13

blocks 99, the upper surface of said blocks will always present a maximum of area in contact with the lower surface of the wedge 93.

5 It will be noticed that by the above construction I have provided a compact arrangement for compressing material into a plurality of closely adjacent molds and one which permits the bulkhead and other parts 10 to be of minimum size and that by concentrating the thrust against the bulkhead, the same need have but a minimum span.

Although I have described for purposes of illustration one specific embodiment of 15 my invention, it is to be understood that I am not limited thereby to its specific mechanical details but that within the scope of my invention wide deviations may be made therefrom without departing from the spirit 20 of my invention.

Claims:

1. In a fluid actuated press, a cylinder, and a plurality of material operating rams in said cylinder and having surfaces in contacting 25 relation.

2. In a fluid actuated press, a cylinder, a plurality of rams in said cylinder, and said rams being arranged exteriorly to each other and having surfaces in contacting relation.

30 3. In a fluid actuated press, a cylinder having a closed and an open end, a plurality of rams in said cylinder and extending through said open end, and said rams having surfaces in contacting relation.

35 4. In a fluid actuated press, a cylinder having a closed and an open end, a plurality of rams in said cylinder and extending through said open end, and said rams being arranged exteriorly of each other and having surfaces in contacting relation.

40 5. In a fluid actuated press, a cylinder of circular cross section, a plurality of rams in said cylinder, said rams jointly conforming to the cross section of said cylinder and conforming to each other on radii of said cylinder.

45 6. In a mold press, a mold block having a plurality of closely adjacent mold chambers, plungers for said chambers, a cylinder below said mold block, rams in said cylinder for operating said plungers, and said rams being each disposed beneath a mold chamber.

55 7. In a mold press, means providing a plurality of closely adjacent mold chambers, a cylinder symmetrically aligned with the total of said chambers, a piston in said cylinder, said piston being divided into a plurality of rams of number corresponding to the number of mold chambers and on longitudinal planes extending between said mold chambers, and means for causing said rams to operate on the material placed in said mold chambers.

60 8. In a mold press, a base comprising a

cylinder, a bulkhead above said cylinder, columns for supporting said bulkhead, a plurality of mold chambers at said bulkhead, and rams in said cylinder for compressing material in said molds.

70 9. In a mold press, a base comprising a cylinder, a bulkhead above said cylinder, columns disposed around said cylinder for supporting said bulkhead, a plurality of mold chambers at said bulkhead, and rams of equal area in said cylinder for compressing material in said molds.

75 10. In a mold press, a base comprising a cylinder, a bulkhead above said cylinder, columns disposed around said cylinder for supporting said bulkhead, a plurality of mold chambers at said bulkhead, and rams in said cylinder for compressing material in said molds.

80 11. In a fluid actuated press, a cylinder, a piston therein divided longitudinally on a diametrical plane into two rams, means for subjecting said rams to fluid pressure, and means for opposing the force of such fluid tending to press said rams together.

85 12. In a fluid actuated press, a cylinder, a piston therein divided longitudinally on a diametrical plane into two rams, means for subjecting said rams to fluid pressure, and fluid pressure means for opposing the force of such fluid tending to press said rams together.

90 13. In a fluid actuated press, a cylinder, a piston therein divided longitudinally on a diametrical plane into two rams, means for subjecting said rams to fluid pressure, and one of said rams being cut away to provide a chamber on its side adjacent the other ram.

95 14. In a fluid actuated press, a cylinder, a plurality of rams with surfaces in contact and jointly fitting said cylinder, and means tending to force said rams away from each other.

100 15. In a fluid actuated press, a cylinder, a plurality of rams with surfaces in contact and jointly fitting said cylinder, and fluid pressure means tending to force said rams away from each other.

110 16. In a fluid actuated press, a cylinder, a plurality of rams with surfaces in contact and jointly fitting said cylinder, and a chamber formed in the contacting surface of one of said rams.

115 17. In a fluid actuated press, a cylinder, a plurality of rams jointly fitting said cylinder, chambers formed between the facing portions of said rams, and said rams being so shaped and the chambers so arranged and of such size that the inwardly acting pressure between the cylinder and said rams is to some extent neutralized.

120 18. In a fluid actuated press, a cylinder, a piston divided longitudinally on radial planes into a plurality of rams, and one of the contacting surfaces of each of said rams

- having a chamber formed entirely across said surface and located intermediate the ends of said ram.
19. In a mold press, a plurality of closely adjacent material receiving chambers, plungers for operating upon the material in said chambers, rams for actuating each plunger, and a common cylinder for said rams.
20. In a mold press, a plurality of closely adjacent material receiving chambers, plungers for operating upon the material in said chambers, rams of equal effective area for actuating each plunger, and a common cylinder for said rams.
21. In a mold press, a mold having a plurality of chambers for receiving material to be molded, a plunger for each chamber, a ram for each plunger, a common cylinder for the rams, and the effective areas of said rams bearing to each other the same ratio that the material capacity of the chambers bear to each other.
22. In a mold press, a mold having a plurality of chambers for receiving material to be molded, separate rams for causing the material in said chambers to be operated upon and having effective areas corresponding to the material capacity of said chambers, and a common cylinder for said rams.
23. In a mold press, a cylinder, a plurality of rams in contact and filling said cylinder, a fixed body of liquid beneath said rams, a displacement means for said liquid, and mold compressing means actuated by said rams.
24. In a mold press, a plurality of mold chambers, plungers for said chambers, common operating means for said plungers, and means for varying the stroke of one plunger relatively to the remainder of said plungers.
25. In a mold press, a plurality of mold chambers, plungers for said chambers, common operating means for said plungers, and means for varying the stroke of one plunger without varying the stroke of the remainder of said plungers.
26. In a mold press, a plurality of mold chambers, plungers for said chambers, common operating means for said plungers, and means for varying the stroke of each of said plungers without varying the strokes of the remainder of said plungers.
27. In a mold press, a plurality of mold chambers, plungers for said chambers, rams for operating said plungers, a common liquid containing cylinder for operating said plungers by rise and fall of pressure of said liquid, and means for varying the stroke of said plungers.
28. In a mold press, a plurality of mold chambers, plungers for said chambers, rams for operating said plungers, a common liquid containing cylinder for operating said plungers by rise and fall of pressure of said liquid, and means for varying the stroke of said
- of one plunger relatively to the remainder of said plungers.
29. In a mold press, a plurality of mold chambers, plungers for said chambers, rams for operating said plungers, a common liquid containing cylinder for operating said plungers by rise and fall of pressure of said liquid, and means for varying the stroke of one plunger without varying the stroke of the remainder of said plungers.
30. In a mold press, a plurality of mold chambers, plungers for said chambers, rams for operating said plungers, a common liquid containing cylinder for operating said plungers by rise and fall of pressure of said liquid, and means for varying the stroke of each of said plungers without varying the strokes of the remainder of said plungers.
31. In a mold press, a plurality of mold chambers, plungers for said chambers, liquid pressure operated rams for operating said plungers, and a common displacement means for raising and lowering the pressure of the liquid for operating said rams.
32. In a mold press, a plurality of mold chambers, plungers for said chambers, liquid pressure operated rams for operating said plungers, common displacement means for raising and lowering the pressure of the liquid for operating said rams, and means for varying the stroke of each plunger.
33. In a mold press, a plurality of mold chambers, plungers for said chambers, liquid pressure operated rams for operating said plungers, common displacement means for raising and lowering the pressure of the liquid for operating said rams, and means for varying the stroke of each plunger without varying the stroke of the remainder.
34. In a mold press, a plurality of mold chambers, plungers for said chambers, liquid pressure operated rams for operating said plungers, common displacement means for raising and lowering the pressure of the liquid for operating said rams, and means for varying the stroke of each plunger while the press is in operation.
35. In a mold press, a plurality of mold chambers, plungers for said chambers, liquid pressure operated rams for operating said plungers, common displacement means for raising and lowering the pressure of the liquid for operating said rams, and means for varying the stroke of each plunger without varying the stroke of the remaining and while the press is in operation.
36. In a mold press, a plurality of mold chambers, a plunger for each chamber, a ram for each plunger, a common cylinder containing a fixed body of liquid for said rams, moving displacement means for said liquid, and means for varying the stroke of each of said plungers.
37. In a mold press, a plurality of mold chambers, a plunger for each chamber, a

- ram for each plunger, a common cylinder containing a fixed body of liquid for said rams, moving displacement means for said liquid, and means for varying the stroke of 5 each of said plungers without varying the stroke of the remainder of said plungers. 38. In a mold press, a plurality of mold chambers, a plunger for each chamber, a ram for each plunger, a common cylinder 10 containing a fixed body of liquid for said rams, moving displacement means for said liquid, and means for varying the stroke of each of said plungers, while the press is in operation. 15 39. In a mold press, a plurality of mold chambers, a plunger for each chamber, a ram for each plunger, a common cylinder containing a fixed body of liquid for said rams, moving displacement means for said 20 liquid, and means for varying the stroke of each of said plungers, without varying the stroke of the remainder and while the press is in operation. 40. In a mold press, means providing a 25 plurality of mold chambers, plungers for said chambers, rams for operating said plungers, said rams being positioned in a common cylinder containing liquid, displacement means for said liquid for causing said 30 plungers to compress the material in said mold chambers, and means for moving said plungers relatively to said rams for ejecting the compressed material from said mold chambers. 35 41. In a mold press, means providing a plurality of mold chambers, plungers for said chambers, fluid operated means comprising a plurality of rams in a common cylinder for moving said plungers for compressing material in said mold chambers, and means for moving said plungers in the 40 same direction for ejecting the compressed material from said mold chambers. 42. In a mold press, means providing a 45 plurality of stationary mold chambers, a plunger for each chamber, liquid operated rams for moving said plungers, a common displacement means for the liquid for said rams and operative to cause said plungers to 50 compress the material in said mold chambers, and means for moving said plungers relatively to said rams for ejecting the compressed material from said mold chambers. 43. In a mold press, means providing a 55 plurality of stationary mold chambers, plungers for each chamber, liquid operated means for giving said plungers a movement for compressing material in said chambers, a common displacement means for said liquid, and means for giving said plungers a movement in the same direction for ejecting the compressed material from said mold chambers. 60 44. In a mold press, means providing a 65 plurality of stationary mold chambers, a plunger for each chamber, liquid operated rams for moving said plungers for compressing material in said mold chambers, a common displacement means for the liquid for said rams, means for moving said plungers relatively to said rams for ejecting the compressed material from said mold chambers, and means for varying the stroke of said plungers independently of the stroke of said rams. 70 45. In a mold press, means providing a plurality of mold chambers, a plunger for each chamber, liquid operated rams for moving said plungers for compressing material in said mold chambers, a common cylinder for said rams, displacement means for said cylinder, means for moving said plungers relatively to said rams for ejecting the compressed material from said mold chambers, and means for varying the stroke of said 75 plungers independently of the stroke of said rams. 46. In a mold press, means providing a plurality of stationary mold chambers, a plunger for each chamber, liquid operated rams for moving said plungers for compressing material in said mold chambers, a common cylinder for said rams, displacement means for said cylinder, means for moving said plungers relatively to said rams for ejecting the compressed material from said mold chambers, and means for varying the stroke of said 80 plungers independently of the stroke of said rams. 47. In a mold press, means providing a plurality of mold chambers, plungers for said chambers; said plungers having an initial position in which said chambers are charged with material, an intermediate position in which said plungers have compressed said material and a final position in which the compressed material is ejected from said chambers; rams having a common cylinder with liquid displacement means for moving said plungers from said initial to 90 said intermediate position, and means for moving said plungers from said intermediate to said final position and serving as an abutment for said plungers in their initial position. 48. In a mold press, means providing a plurality of mold chambers, plungers for said chambers, said plungers having an initial position in which said chambers are charged with material, an intermediate position in which said plungers have compressed said material and a final position in which the compressed material is ejected from said chambers; rams having a common cylinder with liquid displacement means for moving said plungers from said initial to 95 said intermediate position, means for moving said plungers from said intermediate to said final position and serving as an abutment for said plungers in their initial position. 100 110 115 120 125 130

tion, and said last named means being adjustable for varying the initial and final position of said plungers.

49. In a mold press, means providing a plurality of mold chambers, plungers for said chambers; said plungers having an initial position in which said chambers are charged with material, an intermediate position in which said plungers have compressed 5 said material and a final position in which the compressed material is ejected from said chambers; rams having a common cylinder with liquid displacement means for moving said plungers from said initial to said intermediate position, means for moving said plungers from said intermediate to said final position and serving as an abutment for said plungers in their initial position, and said last named means being adjustable for varying 10 the initial position of said plungers.

50. In a mold press, means providing a plurality of mold chambers, plungers for said chambers; said plungers having an initial position in which said chambers are charged with material, an intermediate position in which said plungers have compressed said material and a final position in which the compressed material is ejected 20 from said chambers; rams having a common cylinder with liquid displacement means for moving said plungers from said initial to said intermediate position, means for moving said plungers from said intermediate to said final position and serving as an abutment for said 25 plungers in their initial position, and said last named means being adjustable for varying the final position of said plungers.

51. In a mold press, means providing a plurality of mold chambers, plungers for said chambers; said plungers having an initial position in which said chambers are charged with material, an intermediate position in which said plungers have compressed said material and a final position in which the compressed material is ejected 30 from said chambers; rams having a common cylinder with liquid displacement means for moving said plungers from said initial to said intermediate position, means for moving said plungers from said intermediate to said final position and serving as an abutment for said 35 plungers in their initial position, and said last named means being adjustable for varying the final position of said plungers.

52. In a mold press, means providing a plurality of mold chambers, plungers for said chambers; said plungers having an initial position in which said chambers are charged with material, an intermediate position in which said plungers have compressed said material and a final position in which the compressed material is ejected 40 from said chambers; rams having a common cylinder with liquid displacement means for moving said plungers from said initial to said intermediate position, means for moving said plungers from said intermediate to said final position and serving as an abutment for said 45 plungers in their initial position, and said last named means being adjustable to vary either the initial or final position of said plungers.

53. In a mold press, means providing a plurality of mold chambers, plungers for said chambers; said plungers having an initial position in which said chambers are charged with material, an intermediate position in which said plungers have compressed said material and a final position in which the compressed material is ejected 50 from said chambers; rams having a common cylinder with liquid displacement means for moving said plungers from said initial to said intermediate position, means for moving said 55 plungers from said intermediate to said final position and serving as an abutment for said plungers in their initial position, and said last named means being adjustable to vary one or more positions of any of said plungers independently of the respective positions of the remainder of said plungers.

54. In a mold press, means providing a plurality of mold chambers, plungers for said chambers; said plungers having an initial position in which said chambers are charged with material, an intermediate position in which said plungers have compressed 60 said material and a final position in which the compressed material is ejected from said chambers; rams having a common cylinder with liquid displacement means for moving said plungers from said initial to said intermediate position, means for moving said 65 plungers from said intermediate to said final position and serving as an abutment for said plungers in their initial position, and said last named means being adjustable to vary one or more positions of said plungers.

55. In a mold press, means providing a plurality of mold chambers, plungers for said chambers; said plungers having an initial position in which said chambers are charged with material, an intermediate position in which said plungers have compressed 70 said material and a final position in which the compressed material is ejected from said chambers; rams having a common cylinder with liquid displacement means for moving said plungers from said initial to said intermediate position, means for moving said 75 plungers from said intermediate to said final position and serving as an abutment for said plungers in their initial position, and said last named means being adjustable to vary one or more positions of said plungers.

56. In a mold press, means providing a mold chamber, a plunger for said chamber; said plunger having an initial position in which said chamber is charged with material, an intermediate position in which said material is compressed by said plunger, and a final position in which said compressed material is ejected by said plunger from said mold chamber, means for moving said plunger from its initial to its intermediate 80 position.

57. In a mold press, a mold block having a plurality of closely adjacent mold chambers, a sliding head having an opening therethrough, one or more diaphragms in said opening for dividing it into passages leading to said mold chambers, and a single feed neck in communication with said passages.

58. In a mold press, means providing a mold chamber, a plunger for said chamber; said plunger having an initial position in which said chamber is charged with material, an intermediate position in which said material is compressed by said plunger, and a final position in which said compressed material is ejected by said plunger from said mold chamber, means for moving said plunger from its initial to its intermediate 85 position.

- position, a rock shaft, a lever operated by said rock shaft for moving said plunger from its intermediate to its final position, and determining its initial position, and 5 means independent of said rock shaft and operative while the press is in operation for varying that limit of motion of said lever which determines the initial position of said plunger.
- 10 57. In a mold press, means providing a mold chamber, a plunger for said chamber; said plunger having an initial position in which said mold chamber is charged with material, an intermediate position in which 15 said material is compressed by said plunger, and a final position in which said compressed material is ejected by said plunger from said mold chamber, means for moving said plunger from its initial to its intermediate position, a rock shaft, a lever operated by said rock shaft for moving said plunger from its intermediate to its final position, and determining its initial position, and means independent of said rock 20 shaft and for varying the amplitude of movement of said lever.
58. In a mold press, means providing a mold chamber, a plunger for said chamber; said plunger having an initial position in 30 which said mold chamber is charged with material, an intermediate position in which said material is compressed by said plunger and a final position in which said compressed material is ejected by said plunger from said mold chamber, means for moving said plunger from its initial to its intermediate position, a rock shaft, a lever oscillated by said rock shaft for moving said plunger from its intermediate to its final position and for determining its initial position, and adjustable means independent of 35 said rock shaft and for varying that limit of motion of said lever which determines the final position of said plunger and for adjusting while said press is in operation that limit of motion of said lever which determines the initial position of said plunger.
- 40 59. In a mold press, means providing a mold chamber, a plunger for said chamber; said plunger having an initial position in which said mold chamber is charged with material, an intermediate position in which said material is compressed by said plunger, and a final position in which 45 said compressed material is ejected by said plunger from said mold chamber, means for moving said plunger from its initial position to its intermediate position, a rock shaft, a lever oscillated by said rock shaft for moving said plunger from its intermediate to its final position and for determining its initial position, and means independent of said rock shaft and for varying the throw of said lever while said press is in operation.
- 50 60. In a mold press, means providing a mold chamber, a plunger for said chamber; said plunger having an initial position in which said mold chamber is charged with material, an intermediate position in which said material is compressed by said plunger, and a final position in which 55 said compressed material is ejected by said plunger from said mold chamber, means for moving said plunger from its initial position to its intermediate position, a rock shaft, a lever oscillated by said rock shaft for moving said plunger from its intermediate to its final position and for determining its initial position, and means independent of said rock shaft and for varying that limit 60 of motion of said lever which determines the initial position of said plunger.
- 65 61. In a mold press, means providing a mold chamber, a plunger for said chamber; said plunger having an initial position in which said mold chamber is charged with 70 material, an intermediate position in which said material is compressed by said plunger, and a final position in which said compressed material is ejected by said plunger from said mold chamber, means for moving said plunger from its initial to its intermediate position, a rock shaft, a lever oscillated by said rock shaft for moving said plunger from its intermediate to its final position and for determining its initial position, and means independent of said rock shaft and for varying while said press is in operation that limit of motion of said lever which determines the initial position of said plunger.
- 75 62. In a mold press, a plunger for the mold thereof, a ram for operating said plunger for compressing material in said mold, a lever for giving said plunger movement relatively to said ram for ejecting material from said mold, a rock shaft for operating said lever, and means independent of said rock shaft for adjusting the extent 80 of motion imparted to said lever by said rock shaft.
- 85 63. In a mold press, means providing a plurality of mold chambers, plungers for said chambers, separate levers for moving said plungers, a common operating means for said levers, and means for independently adjusting the range of movement of said levers.
- 90 64. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.
- 95 65. In a mold press, means providing a plurality of mold chambers, plungers for said chambers, a rock shaft, means for oscillating 100 said rock shaft, a pair of arms carried by said rock shaft for moving said plungers, and means for independently adjusting the angular relation of said arms to said rock shaft.
- 110 66. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.
- 115 67. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.
- 120 68. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.
- 125 69. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.
- 130 70. In a mold press, means providing a plurality of mold chambers, plungers for said chambers, a rock shaft, means for oscillating said rock shaft, a pair of arms carried by said rock shaft for moving said plungers, and means for independently adjusting the angular relation of said arms to said rock shaft.

lating said rock shaft, arms loosely mounted on said rock shaft and each arranged for moving a plunger, and means for adjusting said arms relatively to said rock shaft.

- 5 66. In a mold press, means providing a plurality of mold chambers, plungers for said chambers, a rock shaft, means for oscillating said rock shaft, arms loosely mounted on said rock shaft and each arranged for
10 moving a plunger, and other arms carried by said rock shaft and each abutting one of said first arms.

67. In a mold press, means providing a plurality of mold chambers, plungers for
15 said chambers, a rock shaft, means for oscillating said rock shaft, arms loosely mounted on said rock shaft and each arranged for moving a plunger, other arms carried by said rock shaft, and an adjustable motion
20 transmitting means between each of the last named arms and one of the first named arms.

68. In a mold press, means providing a plurality of mold chambers, plungers for said chambers, a rock shaft, means for oscillating said rock shaft, arms loosely mounted on said rock shaft and each arranged for moving a plunger, other arms carried by said rock shaft, each of said last named arms acting to move one of the first named, and an adjustable wedge inserted between each of the arms so moved and the arm for moving it.

69. In a mold press, a plurality of mold chambers, plungers for each of said molds, an oscillating lever for operating each plunger, and an independently adjustable abutment directly engaging each lever and for determining the extent of withdrawal of said plungers from said chambers.

70. In a mold press, a plurality of mold chambers, plungers for each of said molds, an oscillating lever for operating each plunger, an adjustable abutment for each lever, and rotatable eccentrics for adjusting said abutments.

71. In a mold press, a plurality of mold

chambers, plungers for each of said molds, an oscillating lever for operating each plunger, an adjustable abutment for each lever, and rotatable eccentrics for independently adjusting said abutments. 50

72. In a mold press, a plurality of mold chambers, plungers for each of said molds, an oscillating lever for operating each plunger, an adjustable abutment for each lever, and rotatable eccentrics for adjusting said abutments while said press is in operation. 55

73. In a mold press, a plurality of mold chambers, plungers for each of said molds, an oscillating lever for operating each plunger, an adjustable abutment for each lever, and rotatable eccentrics for independently adjusting said abutments while said press is in operation. 60

74. In a mold press, means providing closely adjacent mold chambers, a plunger for each chamber for operating on the material therein, and a single fluid pressure mechanism for operating the plungers and allowing any plunger to move under the influence of said mechanism a greater distance than the remainder of said plungers. 65

75. In a mold press, means providing closely adjacent mold chambers, a mold plunger for compressing material in each chamber, and fluid pressure mechanism comprising a single press cylinder for operating all of said plungers. 75

76. In a mold press, means providing closely adjacent mold chambers, a mold plunger for compressing material in each chamber, and fluid pressure mechanism comprising a single press cylinder for operating the plungers and allowing any plunger to move under the influence of said mechanism a greater distance than the remainder of said plungers. 80 85

In testimony whereof, I have signed my name to this specification.

GEORGE E. WHITNEY.
